UNITED STATES PATENT OFFICE.

BENJAMIN B. HILL, OF PHILADELPHIA, PENNSYLVANIA.

DESIGN FOR A DIE-PLATE.

SPECIFICATION forming part of Design No. 29,823, dated December 20, 1898.

Application filed November 21, 1898. Serial No. 697,101. Term of patent 7 years.

To all whom it may concern:

Be it known that I, BENJAMIN B. HILL, a citizen of the United States, residing at Philadelphia, in the county of Philadelphia and

5 State of Pennsylvania, have invented and produced a new and original Design for a Die-Plate, of which the following is a specification, reference being had to the accompanying drawings.

10 Figure 1 is an elevation of a die-plate, showing my new design. Fig. 2 is an end view of the same.

As shown in the accompanying drawings, there is a body portion A, from which rise 15 side pieces B, as shown in Fig. 1, and depend-

ing from said body are side flanges C, as illustrated in Fig. 2. The side pieces have formed in them curved grooves b, leaving a leaf-like formation between them.

What I claim as new is—

20 The design for a die-plate as herein shown and described.

In testimony whereof I affix my signature, in the presence of two witnesses, this 19th day of November, 1898.

BENJAMIN B. HILL.

Witnesses:

LIZZIE REIFF,
WILLIAM C. STOEVER.
